CLAIM

The ornamental design for a hose coupling fitting interface with male-female sides, as shown and described.

DESCRIPTION

FIG. 1 is a perspective view showing a hose coupling fitting interface with mated male-female sides;

FIG. 2 is a perspective view showing a male side of a hose coupling fitting interface, shown separately from the remainder of the hose coupling fitting interface for ease of illustration;

FIG. 3 is front side elevation view of the male side of the hose coupling fitting interface of FIG. 2;

FIG. 4 is a right side elevation view of the male side of the hose coupling fitting interface of FIG. 2;

FIG. 5 is a left side elevation view of the male side of the hose coupling fitting interface of FIG. 2;

FIG. 6 is a top side elevation view of the male side of the hose coupling fitting interface of FIG. 2;

FIG. 7 is a bottom side elevation view of the male side of the hose coupling fitting interface of FIG. 2;

FIG. 8 is a perspective view showing a female side of a hose coupling fitting interface, shown separately from the remainder of the hose coupling fitting interface for ease of illustration;

FIG. 9 is front side elevation view of the female side of the hose coupling fitting interface of FIG. 8;

FIG. 10 is a left side elevation view of the female side of the hose coupling fitting interface of FIG. 8;

FIG. 11 is a right side elevation view of the female side of the hose coupling fitting interface of FIG. 8;

FIG. 12 is a top side elevation view of the female side of the hose coupling fitting interface of FIG. 8; and,

FIG. 13 is a bottom side elevation view of the female side of the hose coupling fitting interface of FIG. 8.

The broken lines shown in the design in FIGS. 1-13 are included for the purpose of illustrating portions of the hose coupling fitting interface with male-female sides that form no part of the claimed design.
